COMMUNICATION SYSTEM

Vernon M. Bugge and John D. Johnston, Binghamton, N. Y., assignors to International Business Machines Corporation, New York, N. Y., a corporation of New York

Application September 28, 1935, Serial No. 42,641

7 Claims. (Cl. 178—68)

This invention relates to communication systems and more particularly to printing telegraph systems of the non-synchronous type.

The principle of the system employed in the present invention instead of depending on the synchronous operation of the transmitting and receiving units operates on the basis of the transmission of signals of predetermined current values to which the receiving unit will give a definite and different response to each signal. A system of this type is fully disclosed and described in a copending application, Serial No. 737,013, filed July 26, 1934.

The present invention is in the form of an improvement of the system described in the aforesaid application. Briefly and broadly, the system in said application comprises a transmitting unit to initiate character signals consisting of code combinations of impulses having differential current values and polarity. The receiving unit includes relay devices sensitive to said impulse characteristics to control the selection of different circuits, for example, a galvanometer relay of the D'Arsonval type may be used to respond to the different current values employed and the polarity of the impulses, so that the relay brush or armature is positioned to engage one of a plurality of contacts in accordance with the characteristics of the character signal. In addition thereto, another relay device may be used to be responsive only to the number of impulses included in the code combinations, in turn, controlling a device such as a relay to be operated step by step such as the well known type of stepping relay.

A plurality of circuits are associated with the galvanometer relay contacts and with the contacts of the stepping relay and are arranged so that upon the respective positioning of the galvanometer relay and the stepping relay, a single circuit corresponding to the character signal is selected to be energized effecting registration of the selected character.

An object of the present invention is to provide for a more positive system when adverse line and operating conditions are encountered thereby providing a system capable of faster rates of transmission of the character signals.

Another object of the present invention is to provide for increasing the margin of operation of the relay device responsive to the impulse characteristics. In the aforesaid application, the brush or armature of the galvanometer relay was provided to be damped to the extent that the associated contacts were not engaged during

transmission of the short impulses and positioned only upon reception of the longer impulse. The circuit arrangement is such that battery is applied to the brush or armature at all times. In the present invention, a similar device may be used without the extreme damping so as to permit the brush or armature to travel over the associated contacts upon reception of the shorter impulses and yet not effect improper or faulty selection and registration of the characters.

The battery is connected to the said brush only during the timed interval the long impulse is received.

Still another object of the present invention is to compensate for the time lag of the various relay control circuits, for example, the stepping relay circuits.

Still another object of the present invention is to provide for restoring the conditioned and operated circuits to normal under control of the recording unit, in contradistinction to, a predetermined timed delay circuit independent of the receiving unit as described in the aforesaid application.

Various other objects and advantages of the invention will be obvious from the following particular description of one form of mechanism embodying the invention or from an inspection of the accompanying drawings; and the invention also constitutes certain new and useful features of construction and combination of parts hereinafter set forth and claimed.

In the drawings:

Fig. 1 is a schematic diagram showing one form of the connections of the impulse transmitter.

Fig. 2 is a preferred form of the code used in conjunction with the present invention.

Fig. 3 is a schematic diagram showing one form of circuit arrangement of the receiving system.

Referring now to Fig. 1, a plurality of pulse wheels or disks 14 are shown with a combination of conducting segments 16 thereon. The arrangement and number of conducting segments 45 for each disk corresponds to the code shown in Fig. 2, for example, the character "S", the code of which is current value 1, positive polarity and four impulses, namely, three short impulses and one long impulse. Therefore, on the disk 14 for the character "S", four conducting segments 16 are disposed thereon so that the three short pulses of current are conducted before the long segment engages the contacts 17 to transmit the long impulse of its corresponding current value.

It is to be noted that for characters represented by a plurality of impulses the last impulse is always a long impulse the significance of which will be understood as the description progresses.

5 Each disk therefore has disposed thereupon the number of segments to correspond to the number of impulses in its particular code. It is sufficient to mention that upon depression of a character key of the typewriter (not shown) its corresponding disk 14 is released to complete one revolution, thereby conducting the proper increment of current value, polarity and the number of impulses representing the character, to the connected line network. A further description of the transmitting system may be had by referring to the said prior application in which the transmitting typewriter and mechanism for releasing the pulse wheels is shown and completely described. Since this mechanism forms no part of the invention, it is deemed unnecessary to repeat such description.

With reference now to Fig. 3, the code combination of impulses consisting of predetermined characteristics are received over the line associated with the galvanometer relay 20 and line relay 21. The galvanometer relay 20 is shown to comprise an energizing coil 22 connected directly across the line and adapted to be energized in accordance with the various current strengths 30 and polarity impressed thereupon to control the positioning of the armature 23 with respect to the associated contacts 24. It is to be noted that there are eight contacts 24, four contacts corresponding to the four increment current values of 35 positive polarity and four contacts for the four negative current values. Therefore, upon receipt of the character impulses, either the short or long impulses, the armature 23 is positioned to engage the proper contact 24 in accordance 40 with the character signal transmitted.

To continue with the example, for character "S", the armature 23 is positioned to contact 24-1 of the positive group of contacts, for it is remembered that the code combination thereof is 45 four impulses of the first current value and positive polarity.

Permitting the armature 23 to be responsive to both the short and long impulses and thereby to be positioned engaging the corresponding contacts 24 accordingly, it is obvious that the instrument needs no precise damping features, resulting therefore in the possibility of utilizing a less expensive selecting instrument, thus enhancing the practical value of the system.

55 The relay device 21 also associated with the line is designed to be responsive only to the number of impulses included in the code combinations and transmitted accordingly. To assure accurate operation of the system the relay 21 should be a sensitive and fast operating relay, one type which may be provided therefore is a galvanometer relay similar to relay 20, however, a single contact 25, normally open, as shown, is all that is required. In addition thereto to 60 provide for uni-directional operation a bridge rectifier unit 26 is interposed between the line and relay device 21.

Connected to armature 27 of relay 21 by conductor 28 is the operating coil 29 of stepping relay 30, which is of a type well known and requires no further description, and also fully described in the aforesaid application. It is sufficient to mention that for each impulse received, that is, every time the relay 21 is energized to close the associated contact 25, grounded battery 31 through

normally closed contact 38a is connected to the coil 29 operating the stepping relay 30, thereby causing the stepper brush arm 32 to be stepped ahead to the adjacent contact 33.

Release coil 34 associated with the relay 30 5 controls the resetting of contact arm 32 to the normal position as indicated in the drawings, upon the energization thereof.

Relay 35 is also connected to armature 27 and is designed to be a slow operating relay. It was 10 mentioned that relay 21 is operated upon receipt of all impulses closing the contact 25, however, the timed interval the contact 25 is closed by the shorter impulses is not sufficient to permit grounded battery 31 to operate relay 35. It is 15 only the longer impulses which energize the relay 21 closing the contact 25 to connect grounded battery 31 to relay 35 for a timed period sufficient to energize the said relay.

It is obvious that the length of time the contacts 25 are closed does not effect the cycle of operation of the stepper relay 30, in that the stepper arm 32 is advanced upon the receipt of each impulse, either a short or long impulse.

Energization of relay 35 operates the associated 25 contacts 36 connecting grounded battery 31 through the normally closed contact 38, conductor 39, to relay 40, energizing the said relay, and establishing a locking circuit for relay 40 through the contacts 41 now closed. Grounded battery 30 31 is also connected to the armature 23 of the galvanometer relay 20 through the now closed contact 42.

It was mentioned hereinbefore that the armature of relay 20 could be undamped so as to engage the associated contacts 24 during its travel due to the receipt of the character pulses. It was shown that battery is not connected to the said armature until the receipt of the long impulse, and for this reason, it is not possible to 40 energize any of the associated selector relays 43 to 50 until the long impulse is received and in this manner cause a registration of an unwanted character.

Energization of any one of the selector relays 45 43 to 50 establishes a locking circuit for the corresponding relay through the associated contacts 51 to 58 as follows: from grounded battery 31 through normally closed contact 38, conductors 39 and 59, the particular associated and corresponding contact of the said contacts 51 to 58 and the said particular selector relay of the group of relays 43 to 50 to ground 60. Operation of the particular selector relay permits a circuit to be conditioned through the now closed and associated contact of the group of contacts 61 to 68 to energize the associated group control relay of the group of relays 69 to 76, as follows: grounded battery 31, through normally closed contact 38, conductor 39, now closed contact 36, and common conductor 77 to energize the particular group control relay thereby closing the associated contacts a to d.

It is obvious from the description thus far, that the group control relays can only be operated 65 when and only when the long impulse is received. The said impulse controls the connection of battery to armature 23 of relay 20 and also the connection of battery through contact 36 to the group control relays. From the above it is seen 70 how a particular group control relay is selected in accordance with the impulse characteristics due to the positioning of armature 23.

Operation of a group control relay selects from the total number of circuits associated with the

group control relays, four predetermined circuits associated with the *a* to *d* contacts. Selection of a single circuit from the group of said predetermined circuits to correspond to the received character signal is effected by the stopping relay 30.

The arm 32 is positioned to engage one of the four contacts 33 in accordance with the number of impulses included in the code combination of 10 the transmitted character signal. Grounded battery 31 is then effective to energize the selected circuit due to the completion of the said circuit through one of the stepper contacts 33, brush arm 32, normally closed contacts 78a to ground 79.

15 Included in each one of the circuits associated with the group control relay contacts *a* to *d* is a solenoid 80, the energization of which is effective to depress a character key of a suitable recorder, such as a typewriter or punch to 20 register the character in accordance with the transmission of the signals. One preferred type of recording device is fully disclosed and described in the aforementioned application in 25 which the solenoid 38 corresponds to the said solenoid 80 in the present invention, and therefore requires no further discussion.

Upon depression or operation of a selected character key, contacts 81 are adapted to be operated. Specific mechanism for this provision 30 is not shown since it is old and well known in the art; one method, which has been used heretofore, is to provide a common bar beneath the key bars of the recorder and arranged so that the depression of the character keys lowers the 35 common bar which in turn causes the common contacts to be closed.

Operation of the contacts 81 connects grounded battery 37 to relay 82, coil 34 of the stepper relay 30 and relay 83 operating the said relays to 40 restore all the energized circuits in the receiving system to normal condition as shown in the drawings.

Operation of relay 82 causes the contacts 38 and 38a to be opened disconnecting battery 37 45 from the operated selector relay of the group of relays 43 to 50 thereby opening the locking circuit established, also disconnects battery from the armature 23 of relay 20 and opens the locking circuit of relay 40, and too, opens the circuit 50 to the group control relays, deenergizing the particular operated relay, in turn opening the associated contacts *a* to *d* and thereby disconnecting battery 31 from the solenoid circuits.

Energization of release coil 34 of relay 30 55 turns the stepper brush arm 32 to the normal position as indicated in Fig. 3, that is to a position so as to engage the unconnected contact 33. Operation of relay 83 opens the normally closed contacts 78 and 78a disconnecting ground from 60 the brush arm 32 and coil 29 of relay 30 thereby assuring that no faulty operations of the recording unit on the stepper relay may be made.

The operation of the receiving circuit just described will now be explained for the reception of a particular character signal, namely, for the character "S". It was mentioned hereinbefore that the code combination of said character is four impulses of the first current value of positive polarity, therefore upon receipt thereof, the armature 23 of the galvanometer relay 20 is positioned to engage the contact 24-1 of the positive group. However, so long as battery 37 is disconnected from the armature 23, the final selection of the circuits and energization thereof corresponding to the character signal cannot be made.

Reception of the four impulses causes relay 21 to be operated four times successively permitting grounded battery 31 to energize the coil 29 of stepping relay 30 accordingly and thereby positioning the brush arm 32 to engage contact 33-4, 5 the engagement of said contact is maintained until the brush arm 32 is released due to the energization of release coil 34.

In accordance with the description set forth, relay 35 remains inoperative during the reception 10 of the three short impulses of the code, however, the long impulse energizes relay 21 for a timed interval sufficient for battery 31 to energize relay 35 and operate the associated contacts 36. Battery 31 is now connected to relay 40 to operate 15 said relay, establishing a locking circuit therefor through the associated contact 40.

During the timed interval of the reception of the long impulse armature 23 is positioned to engage contact 24-1 of the positive group, so 20 that battery 37 is now connected through contact 42 (now closed), armature 23, contact 24-1 of the positive group, selector relay 46 to ground, operating said selector relay to close the associated contacts 54 and 64. A locking circuit for 25 relay 46 is established through contact 54, and through contact 64, battery 37 is connected through contact 36 and conductor 71 to energize group control relay 72 operating the associated 30 contacts *a* to *d*. The solenoid circuits for characters S, Z, A, and SP are connected to the said *a* to *d* contacts, however, only the "S" circuit becomes operative due to the said positioning of brush arm 32 of relay 30 so as to engage contact 33-4 thereby permitting battery 31 to energize 35 the solenoid 80 to depress a character key corresponding to the character "S".

Operation of the said character key closes the normally open contacts 81 causing relays 82 and 83 and release coil 34 of relay 30 to be energized. 40 Due to the energization of release coil 34 brush arm 32 is reset to its normal position to engage the unconnected contact 33; energization of relay 83 opens the normally closed contacts 78 and 78a to disconnect ground 79 from the associated circuits; and energization of relay 82 opens the normally closed contacts 38 and 38a disconnecting the batteries 37 and 31 respectively, from the associated circuits to deenergize relays 35, 40, 46, and 72 thereby restoring the conditioned circuits 50 to normal. Upon registration of the character "S", contacts 81 are opened de-energizing relays 82 and 83 and release coil 34 to permit further conditioning and operation of the character solenoid circuits in accordance with the subsequent 55 transmission of the character signals.

While there has been shown and described and pointed out the fundamental novel features of the invention as applied to a single modification, it will be understood that various omissions and 60 substitutions and changes in the form and details of the device illustrated and in its operation may be made by those skilled in the art without departing from the spirit of the invention. It is the intention therefore to be limited only as indicated by the scope of the following claims.

What is claimed is as follows:

1. A communication system of the character described comprising means for transmitting character signals consisting of code combinations 70 of impulses having different current values and polarity, selectively operable means responsive to the current values and polarity of the signals, a device responsive only to the different number of impulses included in the signal code, a plurality 75

- of circuits associated with the said selectively operable means and said device, a power supply normally disconnected from the said selectively operable means, and means upon reception of a predetermined impulse to connect the said power supply to said selectively operable means to effect a selection of a single circuit from the said plurality of circuits in accordance with the signal transmitted.
10. 2. A communication system of the character described comprising means for transmitting character signals consisting of code combinations of impulses having different current values and polarity, selectively operable means responsive to the current values and polarity of the signals, said operable means comprising relay means adapted to be positioned to engage one of a plurality of contact segments in accordance with the current values and polarity of the impulses,
15. 20. a device responsive only to the different number of impulses included in the signal code, a plurality of circuits associated with the said selectively operable means and said device, a power supply normally disconnected from the said selectively operable means, and means upon reception of a predetermined impulse to connect the said power supply to said selectively operable means to effect a selection of a single circuit from the said plurality of circuits in accordance with the signal transmitted.
25. 3. A communication system of the character described comprising a plurality of circuits corresponding to predetermined signals, means for transmitting character signals consisting of code combinations of impulses of different current values and polarity, means responsive solely to said current values and polarity and means responsive only to the different number of impulses to select from the plurality of circuits those which
30. 40. correspond to the transmitted character signals, means to energize said selected circuits, recording means operated by the said selected circuits and means directly controlled by the recording means to deenergize the said selected circuits upon operation thereof.
45. 5. A communication system of the character described comprising means for transmitting character signals consisting of code combinations of impulses having different current values and polarity, a plurality of circuits corresponding to the different characters, a relay device responsive to the different current values and polarity of the signals and means responsive to the different number of impulses of said combinations to select
50. 55. a circuit from the said plurality of circuits, means to energize the said selected circuit, an indicating device operated by the said selected circuit, and means under the direct control of the indicating

device to deenergize the said selected circuit upon operation thereof.

5. A communication system of the character described comprising means to transmit character signals comprising code combinations of impulses having different current values and polarity, a plurality of circuits, means responsive only to said current values and polarity of the impulses and means responsive only to the different numbers of impulses of said combinations to effect the selection of a circuit from said plurality of circuits and means including control circuits to be conditioned during the transmission of the impulses to maintain the selection of said particular circuit upon discontinuance of the transmission of the character signal.

10. 6. A communication system of the character described comprising means to transmit character signals comprising code combinations of impulses having different current values and polarity, a plurality of circuits, a relay device responsive to the current values and polarity of the impulses and means responsive to the different number of impulses of said combinations to effect the selection of a particular circuit from said plurality of circuits in accordance with the character signal transmitted, means including control circuits to be conditioned during the transmission of the impulses to maintain the selection of the said particular circuit upon discontinuance of transmission of the character signal, an indicating device operated by said selected circuit, and means to restore the conditioned circuits to normal condition upon operation of said receiving device.

15. 20. 7. A communication system of the character described comprising means to transmit character signals comprising code combinations of impulses having different current values and polarity, a plurality of circuits, a relay device responsive to the current values and polarity of the impulses and means responsive to the different number of impulses of said combinations to effect selection of a particular circuit from said plurality of circuits in accordance with the character signal transmitted, means including control circuits to be conditioned during the transmission of the impulses to maintain the selection of the said particular circuit upon discontinuance of transmission of the character signal, an indicating device operated by said selected circuit, and means operated directly by said indicating device to restore the conditioned circuits to normal condition upon operation of said indicating device.

30. 35. 40. 45. 50. 55. VERNON M. BUGGE.
JOHN D. JOHNSTON.
